UNITED STATES PATENT OFFICE

ELIZABETH DANNER, OF ST. LOUIS, MISSOURI

DOORCHECK

Application filed March 1, 1928. Serial No. 258,413.

The invention aims to provide an exceptionally simple and inexpensive, yet an efficient check which may be easily inserted in a drilled opening in the hinged edge of a door, and will serve to advantageously cushion the final closing of said door, which is particularly advantageous when spring means or other means are employed to effect the door-closing operation.

With the foregoing in view, the invention resides in the novel subject matter herein-after described and claimed, description being accomplished by reference to the accompanying drawing.

Fig. 1 is a side elevation partly broken away and in section, showing the invention applied.

Fig. 2 is an enlarged horizontal sectional view on line 2—2 of Fig. 1, the door being only partially closed.

Fig. 3 is a duplicate of Fig. 2 with the exception that it shows the door completely closed.

The form of construction selected for illustration in the present application, may be considered as preferred on account of its extreme simplicity, inexpensive nature and ease of application, and this construction will be herein specifically described, with the understanding that variations may be made within the scope of the invention as claimed.

The improved check embodies an outer, one-piece, metal tube 4 which is of uniform diameter from end to end, said tube being open at one end but having a closure 5 at its other end. The numeral 6 denotes an inner, one-piece, metal tube which is of uniform diameter from end to end, is provided with one open end, and is closed at its other end by an integral closure 7 which is preferably considerably thicker than the tube wall, the external face of the closure 7 being convex. This closure is formed with a central, air-escape port 8 from its inner to its outer side.

The two tubes 4—6 are telescoped with each other and disposed in sliding contact to provide an elongated, hollow, cylindrical barrel which is of extensible and retractable nature, said barrel being extensible under

the influence of a coiled, compression spring 9 disposed within it, the ends of the spring being positioned against the closures 5—7.

The cylindrical barrel above described, is adapted for reception in an opening 10 drilled into the hinged edge 11 of a door 12, the outer tube 4 being frictionally held in said opening while the inner tube 6 is free to slide. When the door stands open, this inner tube is projected beyond the hinged edge of the door under the influence of the spring 9. As the door nears closed position however, the closed outer end 7 of the tube 6 comes in contact with the door frame 13, arresting its movement, so that the outer tube 4 must slide toward the door frame as the door closes. This sliding movement is resisted by the spring 9. Moreover, as the door nears its final closed position, the door frame gradually closes the air escape port 8, preventing rapid escape of the air compressed in the hollow barrel incident to door closing. This air however can slowly escape and permit final closing of the door. By providing a door check which thus depends not only upon the action of the spring 9 but upon a pneumatic action, the final closing movement of the door is effectively cushioned and slamming prevented, even though a spring-actuated or other closing device be provided for the door. Such a device is diagrammatically illustrated at D in Fig. 1.

As the closure 7 moves from the position at which it initially contacts with the frame, to the position which it occupies when the door is completely closed, it must slide transversely to some extent upon said frame. The convexedly curved formation of the outer side of this closure greatly facilitates this sliding operation and prevents any possibility of either binding the door against correct closing, or binding the tube 6 in the tube 10 instead of permitting free relative sliding of these tubes.

Preferably, I secure a wear-plate 14 to the frame 13 for engagement with the closure 7. This wear-plate is preferably inset in the frame and secured in place by screws 15, 100

but nothing except friction is necessary to anchor the tube 4 in the opening 10.

I claim:—

5 A door check comprising an outer one-piece tube of uniform diameter from end to end, closed at one end and open at its other end; an inner one-piece tube of uniform diameter from end to end, closed at one end and open at its other end; the closed end of said inner tube being externally convex, inherently rigid and having a central air escape port from its inner to its outer side; said tubes being telescoped in sliding contact with each other to provide a hollow extensible
10 and retractable barrel adapted for insetting in a drilled hole in the edge of a door, and spring means in said barrel for extending said inner tube beyond the above-named drilled hole, said convex end of the inner
15 tube being adapted to rock upon the door frame as the door closes, thereby gradually closing said air escape port as the door nears closed position.

20 In testimony whereof I have hereunto affixed my signature.

ELIZABETH DANNER.
